(57) **CLAIM**

I claim the design for a stackable shelving system, as shown and described herein.

DESCRIPTION

FIG. 1 is a top side perspective view of my stackable shelving system;

FIG. 2 is a top plan view thereof;

FIG. 3 is a bottom plan view thereof;

FIG. 4 is a right side plan view thereof;

FIG. 5 is a left side plan view thereof; and,

FIG. 6 is an end plan view thereof the opposite end being a mirror image thereof.

Where used, the broken line portions of the disclosure are for illustrative purposes only and form no part of the claimed design.
